UNITED STATES PATENT OFFICE.

OSCAR J. JOHNSON, OF CLOQUET, MINNESOTA.

BUTTON-FASTENER.

1,092,573.

Specification of Letters Patent. Patented Apr. 7, 1914.

Application filed September 5, 1913. Serial No. 788,346.

To all whom it may concern:

Be it known that I, OSCAR J. JOHNSON, a subject of the King of Sweden, residing at Cloquet, in the county of Carlton and State of Minnesota, have invented certain new and useful Improvements in Button-Fasteners, of which the following is a specification.

The present invention relates to improvements in buttons and of that type sometimes termed "self-attaching."

The object in view is to provide a button embodying a head or shell adapted to receive an attaching shank, locking means being disposed on the head for engaging the shank automatically as the latter is introduced therewith and operable to disengage said shank by the manipulation of a locking member projecting from said shell.

It is further contemplated to employ a special form of spring for normally holding the locking member in locking position, said spring also forming a closure for the opening provided in the button head through which the locking member projects.

For a full understanding of the present invention, reference is to be had to the following description and the accompanying drawings, in which:

Figure 1 is a plan view of the button head or shell with its cap removed and showing more clearly the locking means. Fig. 2 is a rear view of the shell. Fig. 3 is an end elevation. Fig. 4 is an elevation of the co-operating attaching shank member. Fig. 5 is a vertical sectional view taken on the line 5—5 of Fig. 1.

Throughout the following detail description, and on the several figures of the drawings, similar parts are referred to by like reference characters.

Specifically describing the button of the character hereinbefore mentioned as constructed in accordance with my invention, the numeral 1 designates the head which comprises a shell consisting of the body portion 2 and the cap member 3. Adapted to be received into the head or shell 1 is an attaching shank 4 whereby the button may be properly secured to a garment with due allowance for the thickness of the material.

It will be understood in the application for the foregoing style of button that it may be used for various purposes where a self-attaching article of this nature is desired and slight changes in its construction may be

made without departing from the spirit of the invention and within the scope of the appended claims.

The body portion of the shell designated by the numeral 2 is provided centrally of the same with an opening 5 through which the shank 4 is introduced in securing the button in position. Within the shell 1 is disposed locking means for engaging the shank, which means consist of a locking bar 6 and a spring member 7. The bar 6, as shown most clearly in Fig. 1 of the drawing, is secured at one end by clamping a flange 8 of the body 2 over said end in a manner that will permit free lateral movement of the opposite end of the locking bar. The spring 7 is disposed adjacent the bar 6 and is formed with a straight contact portion 9 normally bearing against the bar 6 while said spring has also a curved portion 10 following the contour of the body portion 2 of the shell and said body portion is formed with a flange 11 which is bent over the curved portion 10 to prevent displacement of the spring and insure proper co-operation of the same with the locking bar 6. The curved portion 10 of the spring 7 moreover, terminates in a resistance arm 12, the extremity of which bears against the straight portion 9 of the spring and positively holds the latter against the locking bar 6. As shown in Figs. 3 and 5 most clearly, the cap member 3 of the shell is bent about the body portion 2 so as to effectively inclose the locking means, a slot 13, however, being provided in the shell and through this slot the free extremity of the locking bar projects a suitable distance for manipulation of the same. This slot 13 is normally covered by means of the angularly bent end portion 14 of the spring 7 so that it will be obvious that when the locking bar 6 is in its normal locking position, the bent portion 14 is disposed over said opening, thereby preventing foreign matter from collecting within the shell, as well as eliminating likelihood of the clothing catching in the slot accidentally.

At a point intermediate the length of the bar 6 and juxtaposed with relation to the opening 5 in the body of the shell said locking bar is provided with a pair of spaced projections or lugs 15. The shank 4 consists preferably of a pointed or tapering head 4', and a base plate 4''. When it is desired in the use of the button hereinbefore described, to attach the same in position, the shank 4 is

inserted through the material and into the opening 5 of the shell thereby engaging the head 4' of the shank 4 over the projections 15 on the locking bar 6, said bar moving under pressure against the tension of the spring 7 as the head is inserted in the manner above mentioned. In detaching the member the projecting extremity of the bar 6 is moved laterally permitting the head 4' of the shank 4 to be withdrawn from the shell.

It will be obvious that the special locking means of my button insures a positive engagement of the detachable shank and that the spring when formed into the shape described presents a very strong tension member for the locking bar.

Having thus described the invention, what I claim as new is:

1. In a button, the combination of a head comprising a shell, an attaching shank adapted to be received in said head; a locking bar disposed in said shell adapted to engage with the shank, means for securing said locking bar, the shell having an opening therein through which the locking bar projects, and means for normally holding said locking bar in locking position, said means co-operating with the shell to also form a closure for the opening aforesaid.

2. In a button, the combination of a shell comprising a body portion, a shank adapted to be received in said body portion, a locking bar disposed in said shell adapted to engage with the shank, a spring adapted to co-

operate with said locking bar to normally hold the latter in locking position, flanges on the body portion of the shell for securing the spring and locking bar to the body portion, the shell aforesaid having a slot 40 through which the locking bar projects to permit lateral movement of the locking bar, and the spring aforesaid having one end bent laterally to form a closure for said slot.

3. In a button, the combination of a head 45 comprising a body portion, a shank adapted to be received in said shell, a locking member secured within the shell, spaced projections carried by said locking member with which the shank is adapted to engage, a 50 spring secured in said shell normally contacting with the locking bar, to hold said projections in locking engagement with the shank, said spring being formed with an 55 resistance arm at one end and being bent angularly at its opposite end, the shell having a slot through which the locking bar projects to permit lateral movement of the same, said slot being normally closed by the angularly bent extremity of the spring 60 aforesaid, and a cap for the shell secured about the body portion substantially as described.

In testimony whereof I affix my signature in presence of two witnesses, herein before

OSCAR J. JOHNSON.

Hilda Bissell, my wife, testifying.
